UNITED STATES PATENT OFFICE

151,685

DESIGN FOR A BOOTEE

Philip F. Eberle and Louis E. Sans,
San Francisco, Calif.

Application June 14, 1948, Serial No. 146,964

Term of patent 14 years

(Cl. D7—7)

To all whom it may concern:

Be it known that we, Philip F. Eberle and Louis E. Sans, citizens of the United States, residing in the city and county of San Francisco, State of California, have invented a new, original, and ornamental Design for Bootee, of which the following is a specification, reference being had to the accompanying drawings, forming a part thereof.

Fig. 1 is a top plan view of a bootee, showing our new design.

Fig. 2 is a side view of the same.

Fig. 3 is a rear view of the same.

Fig. 4 is a front view of the same.

We claim:

The ornamental design for a bootee, as shown.

PHILIP F. EBERLE.
LOUIS E. SANS.
